UNITED STATES PATENT OFFICE

EMIL LEVY, OF LIMA, OHIO

BED DAVENPORT

Application filed August 20, 1928. Serial No. 300,931.

The present invention relates to a bed davenport, and has for its prime object to provide a structure wherein the bed davenport when folded will have the appearance of an ordinary standard davenport, but may 5 be extended into a bed davenport having a standard length, and the structure is so designed as to allow the use of regulation size cushions.

Another very important object of the 10 invention is to provide a bed davenport of this nature which is exceedingly simple in its construction, comparatively inexpensive to manufacture, easy to manipulate, and thoroughly efficient and reliable.

With the above and numerous other objects in view as will appear as the description proceeds, the invention resides in certain novel features of construction and arrangement of parts as will be hereinafter more 15 fully described and claimed.

In the drawings:

Figure 1 is a perspective view of the davenport embodying features of my invention.

Figure 2 is a similar view showing the 20 cushions removed.

Figure 3 is a similar view showing the bed extended, and

Figure 4 is a sectional elevation showing 25 the means for holding the arm extensions to the arms.

Referring to the drawings in detail, it will be seen that the numeral 5 denotes the back of the davenport, and numeral 6 the sides and 30 arms thereof. The numeral 7 denotes the bed portion of the davenport which is foldable in the usual well known manner. The numeral 8 denotes the removable cushion. Thus far all parts described are standard and well 35 known in the art. My invention consists in the provision of extension cushion blocks 9 for the arms of the sides 6, so that the davenport may be made longer than the conventional davenport, and yet use the standard size 40 cushions 8. The cushion arm extensions 9

therefore function as fillers and may be provided with lugs 10 to be received in recesses 11 in the side arms 6, so as to prevent displacement. Other suitable means may be used, if desired.

Thus, it will be seen that this bed davenport, under present practice, is to have standard cushions and at the same time, may be converted into a bed with a regulation size bed davenport spring which is usually about 50 six feet long and four feet wide and the six feet running length of davenport. The side 55 cushions on davenports are about twenty-one inches each, totaling sixty-three inches, while the spring is usually seventy-two inches. By 60 removing the parts 9, this enables the bed davenport spring to be opened out into a bed, and when closed, these parts give the appearance of an ordinary bed davenport, allowing 65 the use of standard cushions.

The advantage of this structure is the six 70 feet long bed and the davenport well proportioned to other furniture, and when used as a davenport cannot be told from the standard 75 davenport.

It is thought that the construction, utility, and advantages of this invention will now be quite apparent to those skilled in this art, without a more detailed description thereof. The present embodiment of the invention has 80 been disclosed in detail, merely for the purpose of exemplification, since in actual practice it attains the features of advantage enumerated as desirable in the statement of the invention and the above description.

It will be apparent that changes in the 85 details of construction and in the combination and arrangement of parts may be resorted to, without departing from the spirit or scope of the invention as hereinafter claimed or sacrificing any of its advantages.

Having thus described my invention, what I claim as new is:

In a bed davenport, a back, sides, having rigid arms, a folding spring structure nor- 90

5 mally confined between said sides below the arms, removable filler blocks normally over-
lyng the folding spring structure at the ends thereof, removable cushions normally dis-
posed on the folding spring structure be-
tween the filler blocks, and means for rigidly
connecting the filler blocks with the arms to
normally hold the folding spring structure
in position positively against rising move-
ment.

10 15 In testimony whereof I affix my signature.
EMIL LEVY.
